Primary Examiner — Darlington Ly(74) *Attorney, Agent, or Firm* — Lucas & Mercanti, LLP;
 Klaus P. Stoffel(57) **CLAIM**

The ornamental design for a rotary hammer, as shown and described.

DESCRIPTION

FIG. 1 is a front view of a first embodiment of the rotary hammer showing the present design;
 FIG. 2 is a rear view thereof;
 FIG. 3 is a top view thereof;
 FIG. 4 is a bottom view thereof;
 FIG. 5 is a right side view thereof;
 FIG. 6 is a left side view thereof;
 FIG. 7 is a top, front perspective view thereof;
 FIG. 8 is a front view of a second embodiment of the rotary hammer showing the present design;
 FIG. 9 is a rear view thereof;
 FIG. 10 is a top view thereof;
 FIG. 11 is a bottom view thereof;
 FIG. 12 is a right side view thereof;
 FIG. 13 is a left side view thereof; and,
 FIG. 14 is a top, front perspective view thereof.
